UNITED STATES PATENT OFFICE.

DE FOREST W. CANDLER, OF DETROIT, MICHIGAN, ASSIGNOR TO EARL HOLLEY, OF DETROIT, MICHIGAN.

PISTON.

Application filed November 10, 1924. Serial No. 748,854.

This invention relates to a piston for internal combustion engines, and specifically adapted to be cast in gray iron, and to have the lightest possible weight consistent with 5 the requisite strength.

A further object of this invention is to facilitate the lubrication of the walls, and the final object is to dissipate the heat from the head of the piston down into the skirt. 10 Figure 1 shows a cross sectional elevation on the plane 1—1 of Figure 2.

Figure 2 shows a sectional plan view on the plane 2—2 of Figure 1.

Figure 3 shows a sectional elevation on 15 the plane 3—3 of Figure 2.

In the drawings, A indicates the head of the piston, B and C the wrist pin bosses. D D D' D are the ribs supporting the piston head A, the ribs terminating in the bosses 20 B and C. E indicates the upper portion of the head provided with the usual number of piston ring grooves.

F F indicate the side wall bearing strips connecting the upper portion of the cylindrical skirt E with the lower portion G. The lower portion G is provided with two annular stiffening rings H forming a channel section. K K are the webs connecting the bosses B C to the lower portion of the 25 skirt G, but the major portion of the side thrust is transmitted from the bosses B C to the bearing strip F F through the webs J J.

These webs J J flare from the side wall 30 bearing strips to the bosses, thus giving a truss construction which provides the requisite strength so that the bearing strips will not be deflected either when they are machined or when the pistons are in use.

The ribs D D are preferably arranged to 35 flare from the bosses to the piston head, whereby the piston head is supported at four points or strips, the purpose being to enable the lightest possible construction to 40 be used.

Finally, the ribs J J have the inherent property of dissipating heat due to their exposed construction, being surrounded on all sides by the crank case air, and thereby they are maintained at a temperature substantially 50 below that of the body of the piston, but slightly above that of the temperature of the air in the crank case which circulates within the piston. The tendency of the bearing strips F F to expand with the body of the 55 piston is thereby counteracted by the fact that the ribs J J do not expand with the body of the piston. This construction therefore gives a less expansion to the bearing strips F F despite the fact that they are 60 integrally connected with the head A E of the piston, which is at a much higher temperature than that of the cylinder bore in which the piston reciprocates.

What I claim is:—

1. In a skeleton piston, in combination, 65 a head, an upper skirt connected thereto provided with the usual number of piston ring grooves, a lower skirt, side bearing surfaces connecting the upper and lower 70 skirts, connecting rod bosses, four webs extending flaringly from said bosses to said piston head and substantially horizontal webs extending flaringly from the central portion of said bearing surfaces to said 75 bosses.

2. A skeleton piston, consisting of a piston head, a skirt comprising an upper portion provided with the usual number of piston ring grooves, a lower portion, bearing strips connecting the upper and lower portion, connecting rod bosses, webs projecting horizontally from the bosses to the bearing strips, four stiffening webs extending flaringly from said bosses to said piston head, 80 whereby the piston head is supported in four 85 places.

In testimony whereof I affix my signature.

DE FOREST W. CANDLER.
